UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

SOLE FOR SPRING-HEEL SHOES.

1,171,879.

Specification of Letters Patent.

Patented Feb. 15, 1916.

Original application filed October 12, 1912, Serial No. 725,480. Divided and this application filed July 3, 1914. Serial No. 848,756.

To all whom it may concern:

Be it known that I, ADAM H. PRENZEL, a citizen of the United States, residing at Halifax, in the county of Dauphin and State 5 of Pennsylvania, have invented certain Improvements in Soles for Spring-Heel Shoes, of which the following description, in connection with the accompanying drawings, is a specification, like reference characters 10 on the drawings indicating like parts in the several figures.

This invention relates to shoes and more particularly to improvements in soles for stitchdown shoes of the type disclosed in 15 my co-pending application, Ser. No. 725,476, filed October 12, 1912, on which application United States Letters Patent No. 1,117,086 were granted November 10, 1914.

An object of the invention is to provide 20 an improved shouldered sole for stitchdown shoes and particularly a shouldered sole which is especially useful in the manufacture of single sole stitchdown shoes having spring heels.

25 A further object of the invention is to provide a shouldered sole for spring heel stitchdown shoes which will present a perfectly smooth surface upon the inside of the shoe and a neat appearance upon the out- 30 side of the shoe.

The preferred method of making the sole constituting the present invention is disclosed and fully described in my co-pending application, Ser. No. 725,480, filed Oct. 12, 35 1912, upon which application United States Letters Patent No. 1,105,694 were granted August 4, 1914, and of which application the present application is a division.

40 A preferred construction of the invention will now be described in connection with the accompanying drawing, and the novel features will then be more particularly pointed out in the claims.

Figure 1 is a perspective view showing a 45 sole after the shouldering operation has been performed on the forepart of the sole; Fig. 2 is a side elevation of the sole showing the underwedge in position between the split parts of the heel end of the sole and the sole 50 sprung to bring its upper surface into a plane with the forepart; Fig. 3 is a perspective view showing the sole after the shouldering operation has been continued about the heel end of the sole; and Fig. 4 is a de-

tail section of the sole showing the preferred 55 form of the shoulder.

In carrying out this invention the sole is first shouldered from a point 2 at the front edge of the heel end of the sole upon one side, about the forepart of the sole to a 60 point 4 at the front edge of the heel end of the sole, or vice versa, upon a channeling machine or other suitable means. This shoulder is preferably formed by cutting diagonally into the sole close to the upper 65 edge and turning up a lip 6 in such a manner that the lip overhangs the cut somewhat. An advantage of this form of shoulder is that when the shoe is made by the process described in United States Letters Patent 70 No. 1,117,086, granted on my co-pending application above referred to, the angle of the upper may be tucked into the cut 8 beneath the overhanging shoulder 6 and the staples used to secure the upper in lasted 75 condition may be inserted in the angle of the cut underneath the overhanging shoulder. The heel end of the sole is then split from the rear end substantially to the points 2 and 4 to form a thin flap 10 between which 80

and the other part 12 of the split end of the sole a spring lift or underwedge 14 may be inserted, this underwedge being tapered to a sharp edge at its forward end. The heel end of the sole is preferably so split that the flap 85 10 is thin, compared to the part 12 of the sole. The underwedge 14 is inserted between the split parts of the sole and is firmly cemented to both parts, and the heel end of the sole offset at 16 to bring its upper surface 90 substantially into one plane. The upper surface of the heel end of the sole is then provided with a shoulder which will form a continuation of the shoulder 6 about the forepart and through the shank of the sole. 95 This shoulder 18 upon the heel end of the shoe is preferably formed by cutting through the flap 10 and into the lift 14, the cut being inclined downwardly from the outer edge of the sole so that the outer edge of the lift 14 100 is substantially of its original thickness. A convenient means for shouldering the heel end of the sole is a beveled rotary cutter which has its greatest diameter at its outer end. It will be noted that the flap 10, being 105 a continuation of the material of the upper surface 20 of the forepart of the sole, forms a smooth bridge over the joint between the

forward edge of the underwedge 14 and the forepart of the sole, thus providing a smooth inside for the shoe. It will also be noted that the outer margin 22 of the lift is so located that it will be secured to the heel end of the sole by the stitches by which the welt and upper are secured to the sole. A shoe can thus be completed, if desired, without using metallic fastenings and in any case 10 without having metallic fastenings upon the inside of the shoe where they are likely to come into contact with the foot. If desired, nails may be inserted in the spring 16 to prevent the sole from breaking down at this 15 point and nails or slugs may be inserted through the margin 22 of the wedge and the corresponding portion of the heel end of the sole to resist the wear of these parts and to reinforce the attachment of these 20 parts to each other and to the upper.

Having described my invention what I claim as new and desire to secure by Letters Patent is:

1. A sole for spring heel shoes having upper and lower flaps at its heel end and a wedge secured between said flaps and having formed about its heel end a shoulder extending through the upper flap into the wedge.
2. A sole for spring heel shoes having upper and lower flaps at its heel end, the

upper flap being comparatively thin, and a wedge secured between said flaps and having formed about its heel end a shoulder extending through the upper flap into the wedge.

3. A sole for spring heel shoes having its heel end offset relatively to the plane of the bottom of the forepart of the sole, said sole having upper and lower flaps forming the heel end of the sole and a wedge secured between said flaps and having formed about its heel end a shoulder extending through the upper flap into the wedge.

4. A sole for spring heel shoes having its heel end offset relatively to the plane of the bottom of the forepart of the sole, said sole having upper and lower flaps forming the heel end of the sole and a wedge secured between said flaps and having formed about its heel end a shoulder extending through the upper flap into the wedge and continued to form a shoulder extending about the forepart of the sole.

In testimony whereof I have signed my name to this specification in the presence of two subscribing witnesses.

ADAM H. PRENZEL.
